UNITED STATES PATENT OFFICE.

JOHN ALONZO, OF DEBORGLIA, MONTANA.

RAILWAY-FROG.

1,273,983.

Specification of Letters Patent. Patented July 30, 1918.

Application filed October 31, 1917. Serial No. 199,532.

To all whom it may concern:

Be it known that I, JOHN ALONZO, a subject of the King of Italy, residing at Deborglia, in the county of Mineral and State 5 of Montana, have invented certain new and useful Improvements in Railway-Frogs; and I do declare the following to be a full, clear, and exact description of the invention, such as will enable others skilled in the art to 10 which it appertains to make and use the same.

My invention has for its principal object to provide an improved type of frog for use in connection with railway switches, the de- 15 vice being so constructed as to prevent clogging from snow, ice and the like.

A further object is to so construct the frog as to eliminate the usual guard rails which are employed upon the frog now in use in 20 order to guide the wheels along the same. The space between such guard rails and the line rails often become clogged with snow and ice and cause considerable trouble, all of which is eliminated by the present invention. 25 Furthermore, a great many feet of rails and other track material are thus saved, as well as labor to keep them in repair.

A still further object of the invention is to so construct the diverging rail terminals on 30 opposite sides of the usual V rail, as to prevent catching of a person's foot therein and to also prevent injury to the track or frog in case a derailed car approaching the switch should strike the end of either ter- 35 minal.

With the foregoing general objects in view, the invention resides in the novel features of construction and unique combinations of parts to be hereinafter fully described and 40 claimed, the descriptive matter being supplemented by the accompanying drawings which form a part of this specification and in which:—

Figure 1 is a top plan view of a railway 45 switch showing the application of the improved frog;

Fig. 2 is an enlarged top plan view of the frog;

Fig. 3 is a side elevation with parts broken 50 away and in section;

Fig. 4 is a central longitudinal section on the plane of the line 4—4 of Fig. 2;

Figs. 5, 6, 7 and 8 are vertical transverse sections on the planes indicated respectively 55 by the lines 5—5, 6—6, 7—7 and 8—8 of Fig. 3;

Fig. 9 is a transverse section on the plane indicated by the line 9—9 of Fig. 2;

Fig. 10 is a horizontal section on the plane of the line 10—10 of Fig. 3; and

Fig. 11 is a perspective view of the two bridging blocks.

In the drawings above briefly described, the numeral 1 designates the usual V rail, one rail 2 of the siding being joined to one 60 arm of said V rail, while one of the rails 3 of the main track is joined to the other arm of said V rail. On opposite sides of the rail 1, and extending parallel therewith, are the diverging terminals 4 and 5 of the two 65 switch rails 6. The ends of the terminals 4 and 5 are bent outwardly as indicated at 7 and are beveled downwardly as shown at 8. Filler bars 9 are interposed between the terminals 4 and 5 and the V rail 1 and the outer 70 ends of these bars are also beveled as shown at 10.

By the bevels 8 and 10, there is no danger of a person's foot being caught in the frog and thus the latter does not have to be 80 plugged up in the usual manner by wooden blocks. Furthermore, in case the wheel of a truck which has jumped the track, should come in contact with the terminals 4 and 5, the beveled ends thereof will direct the 85 wheels upwardly onto the track. This is of great advantage, since the entire frog is not longitudinally displaced as now commonly occurs when a wheel strikes one of its terminals.

Positioned between the closely spaced ends of the terminals 5 adjacent the pointed end of the V rail 1, and adapted to bridge the gaps between said V rail and terminals, are two vertically movable bridging blocks 11, 95 these tongues being preferably shaped as shown most clearly in Figs. 6, 7 and 11. The bridging blocks 11 rest on suitable cams 12 carried by rock shafts 13, these shafts being connected for simultaneous movement 100 by a suitable link 14 which is pivoted to crank arms 15 with which said rock shafts are provided. The cams are so arranged that when one bridging block 11 is raised, the other is automatically lowered, and in 105 order to insure that this lowering shall take place, the tongues are preferably connected to the cams by chains or the like 16. Also, in order to prevent possible endwise shifting of the bridging blocks 11, links 17 are provided.

The rock shafts 13 are mounted in suit-

able bearings 18 which are bolted or otherwise secured to the opposite sides of a longitudinal sill 19, said bearings having vertical passages 20 which permit water to drain therefrom so that it will not freeze and interfere with turning of the shafts. The sill 19 is provided with a longitudinal slot 21 which opens through its upper and lower sides, and the portions of the sill on opposite sides of the slot are sharpened along their upper edges as indicated at 22, so that the accumulation of water and the formation of ice is prevented. The portions of the sill 19 upon which the cams 12 rest when in raised or operative position, are preferably flat as indicated in my co-pending application, Serial No. 199,533, filed Oct. 31, 1917, and guards 23 such as those described and claimed in said application, are provided to prevent the possible accumulation of ice upon the portions in the sills engaged by said cams when the latter are raised.

A pair of hangers 24 and 25 are provided for supporting the opposite ends of the sill 19, both of said hangers being formed of two vertical sections 26 whose upper ends are shaped for engagement with the outer sides of the terminals 4 and 5, while the lower ends of said sections are provided with registering notches 27 in which the ends of the sill 19 are received. Bolts 28 are passed through the two sections to hold them together, the lowermost of said bolts passing through the ends of the sill 19, while the upper bolts extend through the terminals 4 and 5, the upper bolt of the hanger 25 passing through the inner ends of the spacer bars 9 and through the pointed end of the V rail 1, while the upper bolt of hanger 24 extends through a spacing block 9^a interposed between the closely spaced ends of said terminals.

In most cases, the hanger 25 will be provided with a foot 29 which is spiked or otherwise secured to a suitable sleeper or the like 30, positioned in the bottom of a pit 31 in which the entire operating means of the frog is located, and it will be understood that both hangers could well be provided with such feet if desired, or that in some cases, no such feet need be used.

Extending between the two hangers 24 and 25 and supported on removable rods 31 are guard plates 32 which coöperate with said hangers in forming a housing for the several moving parts of the frog, whereby the danger from clogging is rendered impossible.

Another feature preferably employed is a base plate 33 to which the V rail 1 and the terminals 4 and 5 are rigidly secured, whereby creeping which might otherwise move these parts into improper relation, is prevented. This base plate, however, forms no part of my invention, having been previ-

ously used on railway frogs for the same purpose.

One of the rock shafts 13 is connected to an operating shaft 34 which is linked at 35 to the operating means 36 for throwing the switch tongues, whereby when the switch is thrown to one position or the other, the proper tongue 11 will be raised. All of the operating mechanism is preferably housed to prevent clogging by sand, snow and ice, and if the improved frog is used in connection with the switch described in the above mentioned application, little trouble and expense will be caused in keeping the line open at the several switches.

From the foregoing, taken in connection with the accompanying drawings, it will be obvious that the provision of the vertically moving bridging blocks 11 will guide the wheels through the frog, the usual guard rails being therefore unnecessary. I wish to emphasize the fact that several parts of the improved frog may be constructed of track material of the types now in common use, and parts of old frogs may be remodeled and used, so that the new frog will be inexpensive and easy to manufacture. I also attach great importance to the fact that the novel construction of the frog prevents clogging thereof from snow, ice or sand. Furthermore, the beveled ends of the terminals 4 and 5 are highly advantageous characteristics as above stated. They also permit the use of shorter spaces than those in the old frogs in which a person's foot might be caught and which are easily clogged.

Since probably the best results are obtained from the several specific details shown and described, these details are preferably employed, but I wish it understood that within the scope of the invention as claimed, numerous minor changes may well be made.

I claim:

1. In a railway frog, the combination of a V rail, diverging rail terminals on opposite sides of said V rail and parallel with the arms thereof, a pair of bridging blocks movable vertically between said terminals at the point of said V rail to bridge the gap between the latter and either terminal, a pair of hangers depending from said terminals adjacent the ends of said bridging blocks, a longitudinal sill below said bridging blocks and secured at its ends to said hangers, and cams mounted on said sill for raising and lowering said bridging blocks.

2. In a railway frog, the combination of a V rail, diverging rail terminals on opposite sides of said V rail and parallel with the arms thereof, a pair of bridging blocks movable vertically between said terminals at the point of said V rail to bridge the gap between the latter and either terminal, a pair of hangers depending from said termi-

nals adjacent the ends of said bridging blocks, each hanger being formed of two vertical sections whose upper ends are shaped to engage the outer sides of said terminals, the lower ends of said sections having notches in their inner edges, a longitudinal sill whose ends are received in said notches, transverse bolts passing through the upper ends of said sections and the rail terminals, additional transverse bolts passing through the lower ends of said sections and through the ends of said sill, and cams mounted on said sill for raising and lowering said bridging blocks.

3. A structure as specified in claim 2, together with spacers interposed between said

terminals at the ends of said bridging blocks, said first named bolts passing through said spacers.

4. A railway frog comprising a V rail, a pair of diverging rail terminals on opposite sides thereof, the widely spaced ends of said terminals being curved outwardly and beveled downwardly, and a pair of filler bars between said terminals and said V rail and having their outer ends beveled downwardly adjacent the bevels of said terminals.

In testimony whereof I have hereunto set my hand in the presence of a subscribing witness.

JOHN ALONZO.
